UNITED STATES PATENT OFFICE.

THOMAS MANLEY, OF PRINCE ALBERT, NORTH-WEST TERRITORY, CANADA.

SAW-MILL DOG.

SPECIFICATION forming part of Letters Patent No. 358,159, dated February 22, 1887.

Application filed April 8, 1886. Serial No. 198,174. (No model.)

To all whom it may concern:

Be it known that I, THOMAS MANLEY, of Prince Albert, North-West Territory, Canada, have invented a new and Improved Saw-Mill Dog, of which the following is a full, clear, and exact description.

My invention relates to the construction of a saw-mill dog that is more particularly intended for dogging small tapering logs, but to which is equally well adapted to the dogging of large straight logs or to the holding of the half-sawed log.

Reference is to be had to the accompanying drawings, forming a part of this specification, in which similar letters of reference indicate corresponding parts in all the figures.

Figure 1 is a view of the dog, one side of the casing being removed and certain sections of the apparatus being shown in section or broken away to disclose the construction of the parts. Fig. 2 is a plan view of the dog. Fig. 3 is a side view representing the dog in connection with a log. Fig. 4 is a vertical sectional view taken on broken line $x-x$ of Fig. 1, and Fig. 5 illustrates certain lever attachments whereby the sawyer may do his own dogging.

In constructing such a dog as is illustrated in the drawings above referred to I provide an inclosing-case, A, formed with horizontal ways $a-a$, which serve as guideways for the sliding rack B, in which the vertically-adjustable bars D D, which carry the teeth C C, are mounted. The rack B is formed from two forward vertical strips, $b-b$, and two lower horizontal strips, $c-c$, which ride in the lower grooves or recesses, a , of the case A, the rear ends of the strips being spaced by an interposed block, c' . (Shown in Fig. 2, and in dotted lines in Fig. 1.) Intermediate horizontal strips, $d-d$, are arranged to ride in the grooves a' of the case A, the strips d being braced by brace-bars d' , which extend forward to connect with the vertical strips or bars b .

The approaching faces of the strips b are formed with recesses $e-e$, in which the vertically-adjustable teeth-carrying strips D are arranged. The teeth C are mounted between the strips D on pivot-pins e' , and are provided with weighted counterbalancing-arms f , which act to hold the teeth against limit-pins f' , so that the normal position of the teeth will

be that in which they are represented in Fig. 1. In order that the teeth may not be thrown over, and also in order that the bars D D may be securely held together, I provide other limit pins or bolts, g , as shown best in Fig. 1. The rack B is operated by means of a lever, E, that is secured to the case A by a tap-bolt, h , the upwardly-extending arm i of the lever E engaging with a stud, j , which is secured to the horizontal arms $d-d$ of the frame B, and projects outward through an elongated slot, j' , formed in the side of the casing, the aperture i' in the arm i being also elongated to allow for the necessary play.

The lever E carries a hand-piece, F, that is provided with a pin, k , arranged to engage with apertures k' , formed in a rack, G, as shown, from which arrangement it will be seen that if the lever E is raised the frame B will be moved outward, and, conversely, if the lever E is depressed the frame will be drawn inward.

In order that the bars D D, which carry the teeth C, may be elevated or depressed as the necessities of the case require, I provide a lever, H, that is pivotally mounted between the horizontal strips $c-c$, and connected by a link, I, with the bars D D, the upper end of the said link I entering the space between the bars D, to which it is connected by a pin or bolt, l , while the lower end of the link is bifurcated to straddle the lever H, to which, as before stated, the link is pivotally connected. This lever H carries a hand-piece, K, that is provided with a pin, m , arranged to be brought into engagement with apertures $n-n$, formed in a rack, L, that is carried by the sliding frame B, the rack being secured to the inner face of two of the strips $c-d$, as indicated.

Although in the construction shown and described the case A constitutes the knee, it will of course be understood that the case could be formed so as to be bolted to the standard or knee of any mill.

In operation it will be seen that the frame B may be advanced or retracted as the necessities of the case require, and it will be understood that when the lever E is moved so that its pin k is in the last or lowest hole the apparatus is then ready to dog the last board.

In Fig. 5 I illustrate a modified construc-

tion, wherein the lever E is provided with an upwardly-extending arm, N, instead of a removable extending arm, F, and wherein the lever H is provided with a bar, M, that is pivotally connected to the end of said lever. The lower edge of the bar M is formed with teeth $\circ\circ$, that are arranged to be engaged by a catch-tooth, O, that is fixed to the casing A. The object of this modified construction is to enable the sawyer to manipulate the dog from a position in front of it.

Having thus fully described my invention, what I claim as new, and desire to secure by Letters Patent, is—

15 1. In a saw-mill dog, the combination, with the case having an apertured rack, the horizontally-movable frame carrying an apertured rack, and the teeth-carrying bars arranged between uprights of the said frame, of the lever pivoted to said frame and connected to a link connected directly to the teeth-carrying

bars, and the additional lever pivoted to said case and connected to said frame, said levers having retaining-detents engaging with the racks of said case and rack, said lever carrying an upwardly-extending arm engaging with a stud which is secured to horizontal arms of the frame and projects outward through an elongated slot formed in the side of the case, substantially as and for the purpose set forth. 25

2. In a saw-mill dog, the combination, with a case, of the adjustable frame B, carrying adjustable tooth-carrying bars D, and manipulating-levers E and H, the lever E being provided with an arm, N, while the lever H is provided with an arm, M, formed with teeth $\circ\circ$, a catch-tooth, O, being formed on the case, substantially as described. 30
